UNITED STATES PATENT OFFICE.

WILLIS G. DODD, OF SAN FRANCISCO, CALIFORNIA.

STEAM-TURBINE.

1,099,970.

Specification of Letters Patent. Patented June 16, 1914.

Application filed August 14, 1913. Serial No. 784,746.

To all whom it may concern:

Be it known that I, WILLIS G. DODD, a citizen of the United States, residing within the city and county of San Francisco, California, have invented certain new and useful Improvements in Steam-Turbines, whereof the following is a specification.

My invention relates to steam turbines, more particularly to that type or class, in which the static energy of steam under pressure has been converted into velocity energy and is repeatedly redirected upon a rotor by means of a coöperating stator, and may be termed a velocity staged turbine.

Heretofore, one of the principal losses occurring in turbines of this type, has been due to spilling, that is, the inability to safely and efficiently gather, all the steam discharged from the nozzle upon the rotor within the initial chamber of the stator, and this loss has been especially marked when a relatively slow speed of the rotor has been required.

A further loss has been due to the inability heretofore, to provide a path through the rotor and stator which would confine the several convolutions of the steam, while traveling through the rotor and stator at different velocities, and prevent them from mixing, and thus dissipate the velocity energy they contain by doing useless work upon themselves.

The object of this invention is to construct a turbine of this class, which can be operated at any desired rotative speed without spilling, and to conduct the steam through the rotor and stator upon a natural path in the form of a coil or helix, and substantially prevent the several coils from mixing or interfering with each other, and thus obtain a higher efficiency than has been heretofore obtained with turbines of this class.

Now I have discovered a method of constructing a turbine of this class by means of which, the object of this invention is obtained, which is, (1.) The pitch, and length of the steam path within the rotor's buckets, must be made to conform substantially to the ratio existing between the acting velocity of the steam issuing from the steam nozzle, and the peripheral velocity of the rotor.

(2.) The coöperating stator must be provided with a series of reversing nozzles, each having a different, but a defined pitch, said pitch being determined for each reversing

nozzle with reference to, the length of the steam path within the buckets of the rotor, the acting velocity of the steam within the buckets of the rotor engaging said reversing nozzle, and the peripheral velocity of the rotor itself.

The features of construction embodying the discovery herein mentioned, will be understood from the following description and the accompanying drawings, in which I have illustrated so much of a turbine of this class, as is necessary to a full understanding of the invention.

In the drawings: Figure 1, represents a vertical section through the steam nozzle, the rotor and the stator of a turbine of the class described and embodying my improvements, all in relative operating position, the broad arrow indicating the direction of rotation. Fig. 2, is a section through the rotor and stator on the line $w-w$, indicating a steam path of substantially constant deflection within the rotor and stator. Fig. 3, is a vertical section through the rotor and stator on the line $y-y$, indicating substantially the egg-shaped form of the recess required between the rotor and stator to provide a steam path of constant deflection, and should be specially constructed to meet the conditions governing each particular case. Fig. 4, is a plan view of the rotor with the stator super-imposed thereon, showing the steam nozzle, the rotor's buckets, and the reversing nozzles of the stator in relative position. Fig. 5, is a series of diagrams illustrating the method of determining the pitch of the rotor's buckets, and the pitch of the reversing nozzles. Fig. 6, is a developed plan of the stator indicating the path of the steam through the rotor and the stator, the broad arrows denoting the active path of the steam through the rotor, and the fine arrows the path through the reversing nozzles within the stator. Fig. 7, illustrates the shape of the steam coil, helix, or worm, formed due to my construction by the steam in its passages through the rotor and stator, from its inlet to the outlet or exhaust.

In the drawings.—A, represents an expansion or accelerating nozzle, by means of which the static energy of the steam is converted into velocity, B—represents a rotor, the buckets of which are preferably formed by inserting within the peripheral recess, thin plates of polished steel —C, these buck-

ets of the rotor have a pre-determined pitch —D, depending upon the conditions under which the turbine is to operate, as will be hereinafter explained.

5 E, represents a stator within which a series of reversing nozzles —F, are formed, preferably by inserting within the recess of the stator, thin plates of polished steel —G. Each of these reversing nozzles has a different, but a pre-determined pitch, depending upon the conditions under which the turbine operates, the reason for which will be hereinafter explained.

Merely for the purpose of illustration, let 15 it be assumed, that a rotor is to be employed twenty-four inches in diameter, fitted with buckets two and nine sixteenths inches in diameter, and is to operate at twelve hundred and fifty revolutions per minute under 20 a steam pressure of one hundred pounds per square inch, and exhaust to atmosphere, we would then have: (1) The velocity of the steam issuing from the steam nozzle and directed upon the rotor would be, approximately 25 2400 feet per second. (2) A rotor 24 inches in diameter and rotating at 1250 revolutions per minute, would have a peripheral velocity of approximately, 131 feet per second. (3) The diameter of the rotor's 30 buckets being 2.57 inches, their circumference would be substantially 8 inches, which, divided by 2, would provide an acting steam path within the buckets of the rotor, of substantially four inches in length. These 35 quantities being known, the required pitch of the rotor's buckets, is now determined as follows: As a portion of the steam velocity is absorbed at each action upon the rotor, for the purpose of illustration, the acting 40 velocity of the steam may be taken as that issuing from the rotor's buckets. As the steam is issuing from the steam nozzle at a velocity of 2400 feet per second and enters the buckets of the rotor, which is moving at 45 a velocity of 131 feet per second, it would emerge therefrom, neglecting frictional losses at, 2400 feet minus 262 feet, or 2128 feet per second. The ratio therefor, between the acting velocity of the steam and the 50 peripheral velocity of the rotor would then be, 2138 divided by 131, or substantially 16, giving a ratio of 16 to 1, indicating that, under the conditions named, the pitch of the buckets, must be equal to one sixteenth, of 55 the length, of the steam path within the buckets, or 4 divided by 16 which is .25 inches, as may be illustrated by diagram —1, of Fig. 5. If a particle of steam moving at a 60 velocity of 2138 feet per second, starts to move across the rotor, along the line, from the point 1 to 1', which is four inches in length, and is moving in the direction indicated by the broad arrow, at a velocity of 65 131 feet per second, the particle will be deflected or carried forward and discharged

at 1" or a distance represented by —a, which is one quarter of an inch. The buckets of the rotor are now formed by inserting within the peripheral recess of the rotor thin plates of polished steel, spaced one quarter of an inch apart. This being the width or pitch —D, of the buckets, required for the rotor, under the conditions named.

Practice has demonstrated that the pitch or diameter of the steam nozzle should not 75 exceed one fifth the diameter of the rotor's buckets, and that it must engage evenly full buckets, and to prevent spilling the rear wall of the steam nozzle, must substantially register with the initial wall of the first reversing nozzle. In the present illustration, the steam nozzle is made of a pitch engaging 80 two full buckets of the rotor, and the initial wall G¹ of the initial reversing nozzle F^a, is located as shown, registering at its receiving end substantially with the rear wall of the steam nozzle in such a manner, that all the steam discharged by the steam nozzle, will be safely and efficiently conveyed within the first reversing nozzle under the conditions 85 named, and redirected upon the rotor ahead 90 of the steam nozzle. The location of the second wall —G², of the reversing chamber is now located as shown parallel with G¹, the pitch of the initial reversing nozzle F^a being 95 equal to that of three of the rotor's buckets, and it may be stated that the pitch of the initial reversing nozzle is always substantially equal to, the pitch of the nozzle plus the pitch of one rotor bucket. Thus 100 constructed, the initial reversing nozzle F^a receives efficiently all the steam discharged from the rotor's buckets in its initial action upon the rotor, in a compact form, reverses it within and along a natural path free from 105 distortion, and redirects it upon the rotor, at substantially the same velocity as received therein.

The pitch of the second reversing nozzle is now determined as follows: Neglecting 110 frictional losses, and assuming that the velocity within the initial reversing nozzle is 2138 feet per second, its acting velocity would then be 2138 minus 262, or 1876 divided by 131, gives substantially 14, indicating that 115 the steam entering the rotor's buckets from the first reversing nozzle, would be carried forward by the rotor before discharge, from the point of entrance to a distance equal to that of —b, as shown, diagram 2, of Fig. 5, 120 or equal to, 4 inches divided by 14, giving substantially .29 inches. A vertical line is now erected from the point —2, of Fig. 6, and the distance —b, is set off, from which point the third nozzle wall or plate G³ is inserted 125 parallel to G² thus forming the second reversing nozzle —F^b, within which the steam is again reversed, and again redirected upon the rotor. Proceeding as before, the available velocity within this nozzle being sub- 130

stantially 1876 feet per second, we have, 1876 minus 262 gives 1624 feet per second as the acting velocity, which divided by 131, gives substantially .12 indicating that the 5 next advance of the steam in passing through the rotor will be equal to 4 divided by 12, giving substantially .33 inches, or a distance equal to $-c$, as shown, diagram —3, of Fig. 5. A vertical line is now erected from 10 point —3, of Fig. 6, and the distance $-c$, is laid off, and the reversing nozzle $-F^c$ is formed as before. The available velocity of the steam within this nozzle being substantially 1624 feet per second, the acting velocity 15 would then be 1624 minus 262, this gives substantially 1362 feet per second, which divided by 131 gives substantially 10, indicating that the next advance of the steam in passing through the rotor will be 4 divided by 20 10, equal to .40 inches, or a distance equal to $-d$, diagram 4, of Fig. 5. A vertical line is now erected from point —4, of Fig. 6, and the distance $-d$, is laid off, and the reversing nozzle F^d is formed as before. The velocity 25 of the steam within this nozzle being 1362 feet per second, its acting velocity would be 1362 minus 262 or 1100 feet per second, which divided by 131 gives substantially 8 indicating that the next advance of the 30 steam in passing through the rotor will be equal to 4 divided by 8 equals .50, or one half inch, or a distance equal to $-e$ diagram —5, of Fig. 5. A vertical line is now erected from the point 5 of Fig. 6, and the distance $-e$ is laid off, and the reversing nozzle F^e is formed as before. The velocity of the 35 steam within this nozzle being 1100 feet per second, its acting velocity would be 1100 minus 262 or 838 feet per second, which 40 divided by 131 gives substantially 6.4, indicating that the next advance of the steam in passing through the rotor, will be 4 divided by 6.4 which gives substantially .63 inches, or a distance equal to $-f$ diagram —6, of Fig. 5. A vertical line is now erected from point —6, of Fig. 6, and the distance $-f$, is laid off, and the reversing nozzle F^f is formed as before. The velocity of the steam 45 within this nozzle being 838 feet per second, its acting velocity would be 838 minus 262 or 574 feet per second, which divided by 131 gives substantially 4.4, indicating that the next advance of the steam in passing 50 through the rotor will be 4 divided by 4.4 or substantially .9 inches, or a distance equal to $-g$ diagram —7, of Fig. 5. A vertical line is now erected from point —7, of Fig. 6, and the distance g , is laid off, and the reversing nozzle F^g is formed as before. The 55 velocity of the steam within this nozzle being 574 feet per second, its acting velocity would be 575 minus 262, or 312 feet per second, which divided by 131 gives 2.38 indicating that the next advance of the steam 60 in passing through the rotor will be 4 di-

vided by 2.38 or 1.7 inches, or a distance equal to $-h$, diagram 8, of Fig. 5. A vertical line is now erected from the point 8 of Fig. 6, and the distance $-h$, is laid off, and the reversing nozzle $-F^h$ is formed as before. The velocity of steam within this nozzle being 312 feet per second, it would emerge from the buckets of the rotor at a velocity of 312 feet minus 262 feet or 50 feet per second, and would require for its exhaust 70 from the rotor a distance equal to $-k$, diagram 9, of Fig. 5. A vertical line is now erected from point 9, of Fig. 6, and the distance $-k$ is laid off, and this distance indicates the space required for the exhaust, and 75 also, gives the least possible distance available for the location of another steam nozzle with its accompanying stator.

It is obvious that when high rotative speeds are required of the rotor, that the 80 pitch of the reversing nozzles will be much greater than as here shown, and in order to hold the coils in proper trajectory, intermediate abutments may be employed.

The method of construction of a turbine 90 of the class described and as herein disclosed, fully indicates and describes step by step the operation performed at each action of the steam upon the rotor, from the primary steam nozzle to the final exhaust, and it 95 shows that the path so formed for the impelling medium under the operating conditions named, is a natural path, free from distortion, eliminates the loss due to spilling, and substantially prevents the several 100 coils of the impelling helix from intermingling and thereby dissipate the useful velocity energy they contain.

It is to be observed that the construction 105 of a turbine of the class described, and as herein disclosed, constitutes within the rotor and stator an interlocking device, analogous to that of a worm gear and pinion depending for its efficiency entirely upon the conditions under which it is designed to operate.

Due to the interlocking of the rotor and stator, forming a natural helical path for the impelling medium through the rotor and stator, an inelastic fluid may be employed 115 as the impelling medium if so desired and under these conditions, the device may be properly described as, a velocity staged fluid motor, comprising a rotor, consisting of substantially a worm gear of uniform pitch, 120 impelled by means of a fluid worm of uniform diameter, the several coils of which are, each of a different pitch and rotating at different velocities, said worm being held in operating position with reference to the 125 rotor by means of a coöperating stator, within which hollow nuts of corresponding pitch are formed, whereby the fluid worm travels through the rotor and stator, from the inlet to the outlet without interfering 130

with each other, thus converting the velocity energy they contain into work which is absorbed and given off by the rotor.

Having thus described my invention, I claim:

1. A velocity staged turbine comprising a nozzle for the impelling medium, a stator within which are located a series of circular reversing nozzles in combination with a 10 rotor, within which are located a series of circular acting buckets the pitch and length of the steam path therein substantially conforming to the ratio existing between the 15 velocity of the impelling medium issuing from the nozzle and the peripheral velocity of the rotor.
2. A velocity staged turbine comprising a nozzle for the impelling medium, a rotor within which are located a series of curved 20 working buckets, the pitch and length of the active path therein conforming substantially to the ratio existing between the acting 25 velocity of the impelling medium and the peripheral velocity of the rotor, in combination with a coöperating stator within which are located a series of reversing nozzles pitched with reference to the length of the steam path within the buckets of the rotor, the acting velocity of the impelling medium

engaging said nozzles and the peripheral 30 velocity of the rotor, whereby a convoluted path is provided for the impelling medium through the rotor and stator, as and for the purpose set forth.

3. A velocity staged turbine comprising a 35 rotor within which are located a series of curved buckets, the pitch and length of the steam path therein conforming substantially to the ratio existing between the acting 40 velocity of the impelling medium and the peripheral velocity of the rotor, a nozzle for the impelling medium engaging one or more full buckets of the rotor in combination with a coöperating stator having a series of reversing nozzles, the pitch of the initial 45 reversing nozzle being substantially equal to the number of buckets engaged by the nozzle plus one more, and in relative position adapted to receive in a compact form the entire discharge from the nozzle and re- 50 direct it again upon the rotor.

In testimony that I claim the foregoing I have set my hand this 8th day of August, 1913, in the presence of witnesses.

W. G. DODD.
